(57) **CLAIM**

The ornamental design for a front panel of a circuit breaker
as shown and described.

DESCRIPTION

FIG. 1 is a front, side perspective view of a first embodiment
of a front panel of a circuit breaker showing our design;
FIG. 2 is a front, side perspective, exploded view of the front
panel of a circuit breaker shown in FIG. 1;
FIG. 3-8 are respective alternative front views of the front
panel of a circuit breaker shown in FIG. 1-2;
FIG. 9 is a bottom view of the front panel of a circuit breaker
shown in any of FIG. 1-8;
FIG. 10 is a top view of the front panel of a circuit breaker
shown in any of FIG. 1-8;
FIG. 11 is a back view of the front panel of a circuit breaker
shown in any of FIG. 1-8;
FIG. 12 is a side view of the front panel of a circuit breaker
shown in any of FIG. 1-8;
FIG. 13 is an opposing side view of the front panel of a
circuit breaker shown in FIG. 12; and,
FIG. 14 is an enlarged rear perspective view of the front
panel of a circuit breaker shown in any of FIG. 1-8.
The broken lines in the drawings illustrate environment and
portions of the front panel for a circuit breaker that form no
part of the claimed design.
